DISPLAY DEVICE

Edward H. Torbeck and Warren Dunn, Altamont,
Ill.; said Dunn assignor to said Torbeck

Application April 21, 1941, Serial No. 389,617

2 Claims. (Cl. 211—1.6)

This invention relates to a display device.

An object of the invention is to provide a display device which includes an upstanding revolute attention arresting member and around the base of which is provided a rotatable platform upon which various items of merchandise may be advantageously displayed.

Another object of the invention is to provide a display device having the hereinabove stated characteristics wherein the upstanding, attention arresting member is internally illuminated, uniformly, throughout its entire length by means of an elongated source of light mounted for easy and convenient replacement by one not skilled in the mechanical arts.

A further object of the invention is to provide a device having the above described characteristics, which is structurally simple, reliable in operation and low in cost.

These and other objects are attained by the means described herein and disclosed in the accompanying drawing, in which:

Fig. 1 is a side view, partly in longitudinal section, of the present device.

As disclosed in the drawing, the device may comprise, generally speaking, a base member 10, a turntable 11 for displaying merchandise, and an upstanding, attention-arresting shaft 12. In the preferred embodiment of the invention, shaft 12 may be provided with a plurality of multicolored spiraled stripes, denoted generally by the numeral 13 which are given an upward flowing effect when they are rotated in a clockwise direction. In order to further augment the effectiveness of the present device, suitable means are provided for simultaneously rotating shaft 12 in a clockwise direction and the display platform 11 in a counterclockwise direction, whereby articles of merchandise positioned on and carried by the display platform will be continuously moved into, through and out of view of a person observing the device.

Turntable 11 may include a depending side wall 14 and a substantially horizontal merchandise display platform 15 the outer perimeter of which may be provided with an upstanding rim 16 to prevent articles of merchandise placed thereon from "walking off" incident to rotation of the platform.

Turntable 11 may be secured to and carried by flange 17 of an internally toothed support-drive gear 18 to which it may be anchored by means of pins 118, or the like. Gear 18 may include a depending collar 19 having a lower edge 20 which makes a bearing contact with the upper surface

21 of base member 10. A rotary motion may be imparted to gear 17 by means of gear 22 suitably anchored to collar 19 by means of hub 23. Gear 22 may be continuously driven by worm wheel 24 which may be operatively secured to drive shaft 25 of an electric motor, denoted generally by the numeral 26. The lower end of a support member 27, may be securely though releasably anchored to base member 10 whereby to project upwardly therefrom, as shown. If desired, the lower end of support member 27 may terminate in an annular collar 28, leg 29 of which may be secured to base 10 by means of screws 30.

15 It will be noted that gear 18 is freely rotatable relative to support member 21. A pinion gear 31 mounted for free rotation about post 32 carried by pinion arm 33 rigidly secured to member 27 by means of pin 34, is adapted to transmit a rotary motion from drive gear 18 to an exteriorly toothed gear 35 which is secured to and carried by the underside of annular disc 36. Gear 35 and disc 36 are freely rotatable relative to support member 27.

20 Shaft 12 preferably comprises a hollow housing of translucent material, such as glass or the like, the outer surface of which may be provided with suitable indicia, such as spiralled stripes 13, or the like. The lower portion of shaft 12 may be suitably anchored to the outer perimeter of disc 36 by means of screws 37, or the like, whereby said shaft will be rotated with said disc. The upper edge of shaft 12 may terminate in a bearing cap 40.

25 The upper end of support member 27 preferably projects upwardly beyond the top edge 41 of shaft 12, and above the upper shoulder 42 of cap 40, as shown. A dome denoted generally by the numeral 43, is adapted to be removably secured 30 to the upper end of member 27, by means of the threaded connection at 44. It will be observed that cap 40 is freely rotatable relative to support member 27 and dome 43.

35 In the preferred embodiment of the invention, support member 27 comprises a length of transparent material, such as clear "Tenite," or the like.

40 Means for illuminating the interior of shaft 12 and dome 43 may be housed interiorly of support member 27. If desired such means may comprise an elongated neon tube 50, or the like, suitably centered within support 27 by means of shims 51 and 52, of cork, rubber, or other suitable substance. A transformer 60 may be mounted to base 10 for supplying the high volt-

age current necessary to excite the neon gas into luminosity.

From the foregoing, it is apparent that when conduit 61 is connected to a suitable source of electrical energy, not illustrated, motor 26 and transformer 60 will be energized with the result that shaft 12 and display platform 15 will be rotated in opposite directions and shaft 12 and dome 43 will be clearly and distinctly visible by reason of being internally illuminated.

Access to tube 50 may be easily controlled by unscrewing dome 43 from support member 27 for exposing the upper end of the tube without disturbing the rotatable elements of the device.

When in operation, rotating, illuminated indicia-bearing shaft 12 very effectively arrests the attention of passers-by, whose attention is then directed to the articles of merchandise carried on platform 15.

It should be understood that various changes and modifications in the structural details of the device may be made, within the scope of the appended claims, without departing from the spirit of the invention.

What is claimed is:

1. In an illuminated display device, a base, a platform revoluble upon said base, a hollow translucent indicia bearing member revoluble upon said platform, a hollow transparent tubular support member fixedly secured to said base and projecting upwardly through said platform and extending coaxially through and projecting beyond the upper end of said indicia bearing member, a translucent dome removably secured to and carried by the upper end of said support member, a bearing cap supported upon the upper end of the indicia bearing member and mounted for relative motion between the upper end of the

indicia bearing member, the lower face of the dome and the support member, said cap adapted to close the upper end of the indicia bearing member and to center the upper end of said member relative to the support member and dome, and an elongated source of illumination extending coaxially through the support member and projecting beyond the upper end of said member into said dome, the lower end of said source of illumination removably secured to said base, said dome controlling access to said source of illumination whereby the same may be removed without disturbing or altering the relationship of the other parts of the device.

15 2. In an illuminated display device, a base, a translucent indicia bearing member revoluble relative to said base, a cap for the free upper end of said indicia bearing member, an elongated hollow transparent support member extending coaxially through said indicia bearing member and projecting through said cap, said support including a lower end secured to said base, and an upper end which projects through and terminates above said cap, an elongated source of illumination extending axially through said support member and projecting beyond the upper end of said member, a translucent dome removably secured to the upper end of said member, said dome adapted to house that portion of 20 said source of illumination which projects beyond the upper end of said support member, and to control access to said source of illumination, said source of illumination adapted to illuminate the dome and the indicia bearing member throughout substantially its entire length.

EDWARD H. TORBECK.
